FOREIGN PATENT DOCUMENTS

DE 2603130 8/1977

Primary Examiner — Wan Laymon(74) *Attorney, Agent, or Firm* — Oblon, McClelland, Maier & Neustadt, L.L.P.(57) **CLAIM**

The ornamental design for a dental matrix band, as shown and described.

DESCRIPTION

FIG. 1 is a top plan view of a dental matrix band according to my design, wherein the bottom plan view thereof is a mirror image of the top plan view.

FIG. 2 is a front, right side perspective view thereof.

FIG. 3 an enlarged top, front, right side partial perspective view thereof.

FIG. 4 is a cross-sectional view thereof along line 4-4 of FIG. 1 and FIG. 2; and,

FIG. 5 is a front elevational view of FIG. 2.

1 Claim, 2 Drawing Sheets(56)
